(57) **CLAIM**

The ornamental design for a portable lawn debris bucket, as shown and described.

DESCRIPTION

FIG. 1 is a front perspective view of a portable lawn debris bucket, showing our new design;

FIG. 2 is a front perspective view of the portable lawn debris bucket depicting a bucket portion pivoted to forward position;

FIG. 3 is a front view of the portable lawn debris bucket;

FIG. 4 is a rear view thereof;

FIG. 5 is a left side view thereof with a right side being a mirror image;

FIG. 6 is a top view thereof;

FIG. 7 is a bottom view thereof; and,

FIG. 8 is a top view of the portable lawn debris bucket depicting a handle portion in a stowed position.
